INVENTOR

BY Victor J. Evans

ATTORNEY

WITNESS: Gerald Hennessy

UNITED STATES PATENT OFFICE.

ANDREW J. RACOSKY, SR., OF REVLOC, PENNSYLVANIA

MERRY-GO-ROUND.

Application filed September 2, 1925. Serial No. 54,111.

This invention relates to an amusement device, the general object of the invention being to provide a rotatable frame having seats thereon, with means for permitting the frame to be rotated by the occupants of the seats.

Another object of the invention is to provide means whereby the frame is rotated through means of a pedaling action of the occupants.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of the device.

Figure 2 is a side view.

25 Figure 3 is a section on line 3-3 of Figure 1.

Figure 4 is a section on line 4-4 of Figure 1.

In these views, 1 indicates a base which 30 may be supported by a concrete base 1' and 2 indicates a vertically arranged shaft supported in the base. This base is formed with a raised central part which is formed at its center with a bearing opening for the 35 lower end of the shaft 2. A cruciform frame 3 is rotatably mounted on the base 1 and said frame includes a disk 4 which has a hub part engaging the shaft. The arms of the frame are bolted to the disk and anti-friction means are arranged between the 40 raised part of the base and the lower face of said disk. The arms of the frame each carry bearings 5 for a shaft 6 which has a beveled gear 7 on its inner end which engages a ring gear 8 carried by the base 1. A frame 9 is carried by each arm of the 45 frame 3, this frame 9 being somewhat similar to a bicycle frame and includes the handle bars 10 and the seat 11. A pedal shaft 50 12 is arranged in each frame 9, and this shaft carries a sprocket 13 over which passes

a chain 14 which also passes over a sprocket 15 on the shaft 6 of the frame. Brace bars 16 extend from a bracket 17 on the top of the shaft 2 to the arms of the frame 3, these bars having turnbuckles 18 therein so that they can be adjusted as to their length. 55

From the foregoing, it will be seen that when the pedal shafts are rotated by the occupants of the seats 11, the shafts 6 will be rotated so that the gears 7 will be caused to roll upon the ring gear 8 on the base 1 and thus the frame 3 will be revolved. The device will not only afford amusement, but will also give the occupants exercise, the same as if they were cycling. 65

It is thought from the foregoing description that the advantages and novel features of my invention will be readily apparent.

I desire it to be understood that I may make changes in the construction and in the combination and arrangement of the several parts, provided that such changes fall within the scope of the appended claim. 70

What I claim is:—

An amusement device comprising a circular base having a centrally arranged raised portion thereon and a ring gear at its periphery, said raised part having a bearing opening at its center, a shaft having its lower end engaging said opening, a disk having a hub part through which the shaft passes, anti-friction means between the raised part of the base and the lower face of the disk, a cruciform frame fastened to the disk, bearing members on the lower face of each arm of the frame, a shaft journaled in each set of bearing members, a gear on the inner end of each shaft meshing with the ring gear on the base, a sprocket on the outer end of each shaft, an upright frame supported on the outer end of each arm of the cruciform frame and including a seat, handle bars and a pedal shaft, a sprocket on each pedal shaft, a chain passing over the sprocket on each pedal shaft and over each of the before mentioned sprockets and brace means connecting the arms of the cruciform frame with the upper end of the shaft. 100

In testimony whereof I affix my signature.

ANDREW J. RACOSKY, Sr.
